SECTION SWITCH

Albert H. Genter, Ross Township, Allegheny County, Pa., assignor to Duquesne Mine Supply Company, Pittsburgh, Pa., a corporation of Pennsylvania

Application November 22, 1938, Serial No. 241,795

3 Claims. (Cl. 191—39)

This invention relates to trolley wire equipment and more particularly to section switches for isolating a branch trolley line from a main trolley line.

The principal object of this invention is the provision of a smooth current collector contacting surface through a trolley switch.

Another object is the provision of a trolley switch with three independent sections forming a trolley contacting surface of uniform character.

Another object is the provision of a trolley contacting switch having a smooth continuous current collector contacting surface with an intermediate section which is energized only when the switch is closed.

Another object is the provision of an over center toggle switch for connecting a branch line through the trolley to the main line.

Another object is the provision of means for supporting a trolley wire section intermediate of two trolley wire sections for the purposes described.

Other objects and advantages appear in the following description and claims.

In the accompanying drawing a practical embodiment illustrating the principles of this invention are shown wherein:

Fig. 1 is a plan view of the section switch.

Fig. 2 is a sectional view taken on the line 2—2 of Fig. 1.

Fig. 3 is an end view of the switch taken on the line 3—3 of Fig. 1.

Fig. 4 is a sectional view taken on the line 4—4 of Fig. 1 showing the intermediate section of the switch.

Fig. 5 is a sectional view taken on the line 5—5 of Fig. 1 showing the knife switch in conjunction with one of the end portions of the sectional switch.

Referring to the drawing, 10 represents two bars preferably made of wood or other suitable electrical insulating material capable of withstanding the tensional stresses subjected to trolley wires. These bars are placed parallel to one another and are arranged to receive the metallic trolley wire supporting members 11 between the ends thereof. Each trolley wire supporting member is made up of two complementary sections 12 and 13 with the dividing line in the center as indicated at 14. The bars 10 and the members 11 are provided with aligned holes for receiving the bolts 15 which hold these principal parts of the mechanism in assembled relation.

Each section 12 is provided with an integral

extension 16 which forms the stationary jaw of a clamp and is provided with a transversely disposed hole 17 therethrough for receiving the clamping bolt 18 which secures the mating jaw 19 of the clamp thereto.

The members 11 and the clamping sections are provided with a longitudinal groove 20 on the inner face adjacent the lower edge for receiving the upper portion of a trolley wire 21 when placed in assembled relation. Vertically disposed teeth 18 similar to those of a screw thread are formed in these grooves for gripping the wire. The trolley wire may be of figure eight cross section, as illustrated, or it may be oval, round or elliptical with a groove on each side adjacent the top. The jaws with their respective complementary grooves and teeth are adapted to receive and clamp the upper portion of most any character of trolley wire and retain it against movement.

Each section 13 is provided with a lug 22 having a socket therein for receiving the feeder wire 23 and is secured by the set screw 24. The stationary contact 25 of the blade switch 26 is formed integral with the section 13 through the strap 27. The contact 25 and the strap 27 lay over one of the bars 10 as indicated in Fig. 5. Other than through the switch blade 28 and the stationary contact members 25, the trolley wire supporting members 11 are electrically insulated from one another.

The intermediate or dummy portion 29 of the trolley wire support is likewise made in two sections or jaw members 30 and 31. The jaw 30 is rigidly secured to one of the bars 10 by means of the bolts 32. The jaw 31 is clamped to section 30 by means of the bolt 33 and the sleeve 34 which extend through a hole in the bar 10. The long bolt and sleeve permit the movable jaw member 31 to be clamped or unclamped without disassembling the bars 10. A shoulder 35 is provided on the inner face at each end of the stationary jaw member 30 as illustrated in Fig. 2 for maintaining alignment of the movable jaw member 31.

The jaw members 30 and 31 are also provided with a longitudinal groove 20 on their inner faces adjacent the lower edge thereof and are provided with vertically disposed teeth or threads for receiving and clamping a short section of the trolley wire in the manner described above. The ends of the intermediate portion or dummy 29 are spaced from the inner ends of the trolley wire supporting members 11, forming air gaps therebetween to prevent the passage of an electric current between these parts.

- Attention is directed to the fact that the structure described may be applied to a suspended trolley wire and after the clamps are set the trolley wire may be severed at the air gaps by sawing the trolley wire. Thus the trolley wire may be suspended in a branch line that is being used continuously without interrupting traffic and when it is desirable to provide a switch for cutting off the branch line the switch may be applied by cutting the trolley wire without altering the existing trolley system or requiring the use of come-alongs or other wire stretching equipment. This is an important advantage of this invention.
- 15 The structure thus far described may be employed in a trolley line as a circuit energizing device for operating a track switch or other similar device, in which case the wire 23 in one supporting member 11 may be connected to the other 20 supporting member 11 forming a jumper electrically connecting the adjacent ends of the trolley wire sections. The dummy section 29 is then connected to a switch operating mechanism which becomes energized when the trolley current collecting device momentarily bridges the air gap between the trolley wire section and the dummy 25 29. Thus a smooth current collecting surface is provided in a circuit energizing device which forms an important object of this invention.
- 30 The blade 28 of the switch 26 is pivotally supported intermediate of its ends on the vertically disposed pin 36 fixed in the transverse arm 37 which is secured to the intermediate jaw member 38 by welding or brazing. A short arm 38 35 is secured to the intermediate portion of the blade 28 and extends at right angles thereto. The outer end of the short arm 38 is provided with an upstanding pin 39 arranged to operate in the slot 40 in the operating lever 41 which is pivoted 40 on the stationary arm 37 as indicated at 42. A spring 43 is secured at one end to the pin 39 and at the other end to the pin 44 on the lever 41, thus providing a short arm toggle switch having a snap action when moved beyond dead 45 center. The contacts 45 on the ends of the blade 28 are held in contact with the stationary contact members 25 under the tension of the spring 43. The shape of these contacts together with the tension of the spring 43, which may be made 50 very great, insures low resistance between the contacting surfaces.
- The outer end of the operating lever 41 is provided with an insulated hand grip 46 with a shield 47 and when thrown from either side to the dead center position the spring 43 completes the action of the switch to engage the contact portions 45 on the ends of the blade 28 with the stationary contacts 25 or to carry them remotely therefrom.
- 55 60 The double arm toggle provides a shorter and faster movement of the operating lever and the switch blade. However the trolley collecting shoe ordinarily precedes the engine when coming from a branch line and the switch is therefore not opened or closed under load.
- 65 The blade switch operating mechanism shown is designed principally for mine trolley systems where ceilings are low and the engineer can reach up and throw the switch by hand or use a stick to tap the operating lever as he travels along, thereby cutting the branch trolley line in service only during the short time it is being used and

thus avoiding short circuiting the main trolley line through a fault along the branch line when not in use. When installing the switch it is preferable to connect the right end to the main trolley line and the left end to the branch, thus permitting the engineer to tap the operating lever in the direction of travel for opening or closing the switch.

The smooth continuous current collecting surface made by the trolley wire in this device eliminates abrupt changes in this surface, thereby eliminating arcing, which not only burns the collector and the wire or substituted bridge but in a mine may ignite explosive gas, causing greater damage. Apparatus of this character for 15 trolley systems are required to be compact and it is impossible to run a current collecting device between a wire to a bridge member without creating a bump which causes an arc. Here the wire forms the contacting surface through the 20 device and no bumps or arcing are produced.

I claim:

1. In a trolley conductor-support the combination of two partible clamping members, each part having a longitudinal groove adjacent the lower 25 edge thereof which grooves coact to hold the upper portion of adjacent conductor-sections, an insulating support for holding said clamping members in spaced relation with the conductors in axial alignment, and a third partible clamp 30 carried on the insulating support intermediate of the two clamping members and arranged to support a short conductor-section of similar character in axial alignment with the other conductor-sections, the ends of the intermediate section 35 being in spaced relation to the ends of the adjacent sections.

2. In a trolley conductor-support the combination of two partible clamping members, each part having a longitudinal groove adjacent the lower 40 edge thereof which grooves coact to hold the upper portion of adjacent conductor-sections, an insulating support for holding said clamping members in spaced relation with the conductors in axial alignment, a third partible clamp carried 45 on the insulating support intermediate of the two clamping members and arranged to support a short conductor-section of similar character in axial alignment with the other conductor-sections, the ends of the intermediate section being 50 in spaced relation to the ends of the adjacent sections, and a switch member mounted on said insulating support and arranged when closed to electrically connect said conductor sections.

3. In a trolley wire section switch the combination of three partible clamping members, a longitudinal groove adjacent the lower edge of each part which coacts to hold the upper portion of adjacent conductor-sections, an insulating support for holding said clamps with the conductors 60 in aligned spaced relation, a contact block electrically connected to each remote clamping member and having an open-faced contact surface, a switch blade mounted on the insulating support adjacent the intermediate clamp member and connected thereto, contacting surfaces on said switch blade complementary to the contact surfaces on said blocks, and a spring connected to said blade for maintaining contact pressure between the corresponding contact surfaces of the 70 blade and the blocks.

ALBERT H. GENTER.
